COMBINED KNOB AND LATCH

Filed July 6, 1927

INVENTOR,
Franz Netschert

BY Fred H. Hayn
ATTORNEY.

UNITED STATES PATENT OFFICE

FRANZ NETSCHERT, OF LOS ANGELES, CALIFORNIA, ASSIGNOR TO THE TECHNICAL GLASS COMPANY, INCORPORATED, OF LOS ANGELES, CALIFORNIA, A CORPORATION OF CALIFORNIA

COMBINED KNOB AND LATCH

Application filed July 6, 1927. Serial No. 203,708.

My invention relates to a combined knob or latch adapted for use in connection with cupboards, drawers and the like, and especially where it is desired that the knob associated therewith will be of ornamental appearance, and at the same time the unlatching of said knob by said latch may be accomplished by the natural movement induced by turning said knob either clockwise or counter-clockwise, which movement is independent of the action of the latch when the door or drawer with which it is associated is closed.

It accordingly is an object of my invention to provide a novel form of combined knob and latch device having a pair of sleeves adapted to coact with each other so that the device may be secured to a support, one or both of said sleeves having means associated therewith whereby said sleeves may be firmly secured to said support, a preferably ornamental knob being positioned in one of said sleeves and adapted to operate a latch in pivotal association with one of said sleeves by a turning movement of said knob, said latch having means for engaging a keeper, said turning movement functioning to release the keeper from the latch, but at the same time permitting an independent vertical movement of the latch for engaging said keeper. The above and further objects and advantages of my invention, as will hereinafter more fully appear, I attain by the device constructed in accordance with the description thereof and illustrated on the drawings forming a part of my application.

Reference is had to the accompanying drawings, in which similar reference characters denote similar parts. In the drawings,

Fig. 1 is a longitudinal sectional view of my device illustrating its association with a support, the latch being shown in engagement with its keeper,

Fig. 2 is an exploded view of the parts of my device with sleeves omitted, which parts are shown in side elevation,

Fig. 3 is a fragmentary side elevation of a slight modification illustrating a wrench engaging means for securing the device to a support,

Fig. 4 is an elevational view of Fig. 3,

Fig. 5 is a side elevational view of a modification in which one of the securing sleeves is in direct alignment with the other,

Fig. 6 is a somewhat enlarged elevational view of the cam means, and

Fig. 7 is a top plan view of the latch.

Describing my invention more in detail, the device as shown in Figs. 1 and 2, comprises a pair of sleeves 2 and 4, the sleeve 2 being externally threaded as shown to engage with the internal threads of the sleeve 4, said sleeves being adapted to be positioned within the hole 6 in the drawer or door 8 of the cupboard or other device 10 which is equipped with any preferred form of keeper 12, secured thereto by any suitable means as the screws 14.

The keeper 14 is adapted to be engaged by the hook 16 of the latch 18, which latch may be in the form of a flattened elongated member, bent or warped as at 20, and provided with a suitable pivot holding portion 22, bored as indicated at 24 (Fig. 7) to house the pivot pin 26, which pivot pin extends through and is anchored in the sleeve 2. The latch 18 is also provided with a preferably flat portion 28, cut as shown in Fig. 7 to provide a means adapted to be engaged by the cam means 30, presently to be more particularly described. It will, of course, be understood that the shape and specific construction of the parts 22 and 28 is immaterial and may in practice be changed.

Associated with the latch 18, and preferably surrounding the pivot pin 26 is a coiled spring 32, which spring has its ends in engagement with the latch 18 and the sleeve 2, so that any turning movement of said latch may be resisted, said latch when turned in either a clockwise or counter clockwise direction by the means presently to be described, will be returned to its original position by said spring. It will also be clear that any other means of mounting said spring may be substituted for that shown and described and still remain within the province of my invention.

The means for operating the latch 18 so that it may be disengaged from the keeper 12 comprises a knob 36, preferably con-

structed of glass or other suitable material, said knob having its base 38 firmly secured in a base 34, preferably spun over the base 38 or secured thereon in any other preferred way.

Preferably integral with the base 34 is an extension 40 which is adapted to fit rather snugly within the thickened portion 42 of the sleeve 2, yet without binding, so that 10 said extension may be turned therein, and within the extension 40 is positioned a headed rivet or other member 44, which may be threaded to said extension as shown, and its head in close engagement with the base 36. 15 To the rivet 44 is secured the cam means 30, either threaded thereon or associated therewith in any other desired manner, said cam means being provided with a projection or cut-away portion 46, which projection is 20 adapted to engage the flat portion 28 of the latch 18 so that when the knob 36 is turned either in clockwise or a counter clockwise direction the latch will be released from the keeper 12, against the action of the spring 32, 25 which spring will return said latch to its original position when the knob 36 is released.

The sleeve 2 may be provided with a rounded portion 48 to be engaged by a pair of pliers so that said sleeve may be screwed 30 home within the support 8, or said portion may take the form of a hexagonal or other nut 48' as seen in Figs. 3 and 4, for engagement with a wrench. The sleeve 4 may also have a suitably shaped flange 50 to be engaged by a pair of pliers or a wrench. It will be clear also that the usual conventional 35 form of washers may be provided.

In Fig. 5 I have shown a simplified form 40 of my invention wherein the sleeve 4' is directly engaged with the threaded sleeve 2', the elongated threaded portion of said sleeve depicted in Fig. 1 being omitted, the latch 18 and knob 36' as well as the other parts, being 45 the same as shown in Fig. 1, and hence need not be further described.

In operation, when the cupboard door or drawer is closed, the inclined hook 16 rides on the extension of the keeper 12, which depresses the latch 18 against the action of the 50 spring 32, and permits said hook to snap into engagement with said keeper. To release the latch 18, the knob 36 is turned either in a clockwise or counter-clockwise direction, the extension 40, and at the same time the cam 55 being turned, the cam projection 46 engaging the flat portion 28, which movement turns the latch 18 on its pivot 26, causing said latch to move downwardly and hence to be disengaged from the keeper 12, the turning 60 movement of the projection 46 causing the portion 28 to be moved upwardly or downwardly, either against or with the action of the spring 32.

While I have thus described my invention 65 with great particularity, it will be clear that

the same may be modified throughout a wide range. I accordingly do not propose to be limited to the exact details of construction shown and described, but reserve the right in practice to make any and all modifications 70 thereof that fall within the scope of the appended claim.

I claim as my invention:

In a cupboard catch, an externally threaded sleeve, closed at one end, a knob having 75 a shank threaded into said closed end, a cam member secured to said shank, and positioned in said sleeve, a cam on the lower end of said member, a catch pivoted within said sleeve at its opened end, a spring for opposing the movement of said catch, means on the inner end of said catch adapted to be engaged by said cam when said knob is turned to operate said catch, and an open ended threaded sleeve adapted to be adjusted on 80 the threads of said first sleeve.

In testimony whereof I have signed my name to this specification.

FRANZ NETSCHERT.
